By Frank Mulligan
Attorney

United States Patent Office.

DANIEL WIEHL, OF CINCINNATI, OHIO, ASSIGNOR TO HIMSELF, PETER W. HAGEN, ANDREW P. LUSK, AND JOHN H. BUCKMAN.

Letters Patent No. 105,155, dated July 5, 1870.

IMPROVEMENT IN LOW-WATER INDICATORS.

The Schedule referred to in these Letters Patent and making part of the same.

To all whom it may concern:

Be it known that I, DANIEL WIEHL, of Cincinnati, Hamilton county, State of Ohio, have invented certain new and useful Improvements in Low-water Indicators for Steam-Boilers; and I do hereby declare the following to be a sufficiently full, clear, and exact description thereof, to enable one skilled in the art to which my invention appertains to make and use it, reference being had to the accompanying drawing making part of this specification.

My invention relates principally to the low-water indicator for which Letters Patent were granted to PETER W. REINSHAGEN, assignor to himself, DANIEL WIEHL, ANDREW P. LUSK, and JOHN H. BUCKMAN, No. 102,433, dated April 26, 1870; and

My invention consists—

First, in the provision, in connection with the balanced floating valve, of a spherical case surrounding the float on the exterior of the boiler, and a connecting-pipe to communicate from the case to the inside of the boiler, the pipe terminating at the required water-line.

Second, in connection with the devices described in the previous clause, of a diaphragm at the lower part of the spherical case, which serves as a guide for the float, and as a break-water for preventing the water as it enters the chamber, from driving the float and valve too hard against the seat.

Third, in a certain peculiar construction of the break-water diaphragm by which a rotary motion is given to the water as it enters the chamber, which serves to enable the valve to keep its own seat clean by an occasional rotary motion on the seat.

Description of the Accompanying Drawing.

Figure 1 is an axial or vertical central section of a low-water indicator embodying my invention.

Figure 2 is a cross-section, exhibiting the shape of the guide and break-water at the bottom of the spherical case.

Figure 3 is a detached perspective view of the under side of the break-water diaphragm, exhibiting the device for causing the water to revolve as it enters the chamber.

General Description.

A represents the outer shell of the boiler, and B a heavy metallic spherical case or chamber, which has a steam-tight joint, b, at the middle, secured by bolts b', and is connected to the boiler-sheet A substantially in the manner shown.

A pipe, C, communicates with the inside of the boiler from the case B, terminating at the lower end at or near the required water-line of the boiler.

The case or chamber B is constructed with a conical valve-seat, D, and is surmounted by a steam-whistle, E.

The float F, which is of sheet metal, and as near spherical as possible, is fitted with a valve-stem, f, and counter-weight f', the latter, although it is guided, as shown, serving to sustain the stem f in the vertical position.

The conical seat D and float F f', are embodied in the Letters Patent No. 102,433, aforesaid.

The provision of the spherical case B to inclose the float on the outside of the boiler, and the pipe C to communicate with the interior of the boiler, enables the valve f to open and close by the falling or rising of the water in the boiler, much more promptly than when the float is located inside the boiler, as, the instant the water falls below the end of pipe C, the case B is emptied of water, and the float F falls so that steam is permitted to pass and blow the whistle.

When the water again rises so as to cover the end of pipe C, the water rushes up and fills the chamber B, floats the ball F, and closes the whistle.

In order to prevent water as it enters the chamber B from driving the float F f' too forcibly against the seat D, I provide the break-water diaphragm G, which prevents the water striking squarely against the bottom of the float F, and directs it wholly up the sides.

The diaphragm G also serves, in the manner shown, as a guide for the weight f' of the float.

The seat D is kept clean automatically, by the occasional rotation of the stem f on the seat, which rotation is caused by the rotary motion of the water as it enters the chamber B.

The water is compelled to rotate on passing the plate G, by the spiral grooves g, which are provided on the under side of the plate, (see fig. 3.)

Claims.

I claim—

1. In connection with the float F, the provision and arrangement of break-water and guide-plate or diaphragm G, operating as described, and for the purpose specified.

2. The spiral grooves g, in the described connection with the float F f and seat D, as described, and for the purpose stated.

In testimony of which invention I hereunto set my hand.

DANIEL WIEHL.
